United States Patent Office

Des. 202,962

Patented Nov. 16, 1965

202,962

SOLARIUM

Mike Tecton, Oklahoma City, Okla.
(5101 45th St. NW, Washington, D.C.)

Filed Jan. 6, 1965, Ser. No. 83,312

Term of patent 14 years

(Cl. D83—1)

FIG. 1

FIG. 2

FIG. 3

FIG. 4

FIG. 5

FIGURE 1 is a front perspective view of a solarium embodying my new design;

FIGURE 2 is a top plan view thereof;

FIGURE 3 is a side elevational view thereof;

FIGURE 4 is a rear elevational view thereof;

FIGURE 5 is front elevational view thereof.

I claim:

The ornamental design for a solarium, substantially as shown and described.
